UNITED STATES PATENT OFFICE

127,588

DESIGN FOR A COMBINATION WORKBENCH AND TOOL CHEST

Frank M. Owen, Pasadena, Tex.

Application March 20, 1941, Serial No. 99,740

Term of patent 14 years

To all whom it may concern:

Be it known that I, Frank M. Owen, a citizen of the United States, residing at Pasadena, in the county of Harris and State of Texas, have invented a new, original, and ornamental Design for a Combination Workbench and Tool Chest, of which the following is a specification, reference being had to the accompanying two-sheet drawing, forming a part thereof, and in which:

Figure 1 is a perspective view of the article, showing the tool compartments partially opened; and,

Figure 2 is a similar view showing the compartments closed.

I claim:

The ornamental design for a combination workbench and tool chest, as shown.

FRANK M. OWEN,
